UNITED STATES PATENT OFFICE.

LEON COHEN, OF ST. LOUIS, MISSOURI.

HAT-SIZE REDUCER.

Application filed September 8, 1927. Serial No. 218,124.

My invention relates to improvements in hat size reducers, and has for its primary object a hat size reducer which presents a relatively wide surface for contact with the head.

A further object is to construct a hat size reducer which is very light in weight and which is more or less ventilating so that it will not heat up the head of a wearer.

10 In the drawings:—

Fig. 1 is an inside face view of the compound flexible strip made use of;

Fig. 2 is an outside face view of the same;

Fig. 3 is an edge view of the same;

15 Fig. 4 is a face view of the elastic member made use of;

Fig. 5 is a top plan view of my completed hat size reducer;

Fig. 6 is a cross section taken on the line 20 6—6 of Fig. 5; and

Fig. 7 is an enlarged section of the compound flexible strip taken on the line 7—7 of Fig. 1.

In the construction of my device I employ 25 a compound flexible strip, which is composed of a relatively wide flexible member 8. This member is formed of, what is known by the trade, as fiber board. This board, while being flexible, still is fairly stiff and will not 30 break down under use. Extending along one face of the strip 8 is a flexible metal strip 9. This flexible metal strip as will be observed, is considerably narrower than the strip 8 and extends longitudinally of the 35 face of the strip 8 and is preferably of the same length so as to support the ends of the strip and keep them from bending over laterally.

Secured to the strip 8 in spaced apart position are sleeves 10. These sleeves have points or prongs 11 formed integral therewith and the strip 9 is secured in position on the strip 8 by pushing these prongs through the strip 8 so that they project from the rear face 45 thereof as illustrated in Fig. 3. The front or elastic member of the reducer is composed of a strip of elastic 12. This strip as illustrated in Fig. 4 is wider than the strip 8 and of less length than said strip. The 50 edges 13 and 14 of the elastic 12 are parallel throughout the major portion of their length but these edges are trimmed off diagonally as illustrated by the numeral 15 at each end of the strip so that the ends 16 of the elastic strip are of substantially the same width as

the strip 8. The elastic is secured in position by forcing one of the end prongs through the elastic adjacent one end. The elastic is then brought around the ends of the strips 8 and 9, drawn across the face of the strips and brought around the opposite end of the strips where the other end prong is pushed through the elastic. This will bow the members 8 and 9 outward from the elastic with the strip 9 between the strip 8 and the elastic, the strip 9, however, being flexible as is the strip 8, bends with this strip and hugs it closely. After this is done a crescent-shaped covering 17 is placed around the elastic and the strip 8. This crescent-shaped cover is constructed of one piece of fabric and has its edges 18 and 19 secured together by stitching. The ends 20 of the casing or covering are also stitched so that a hollow fabric casing is formed. It will be 70 noted from Fig. 6 that the elastic has its edges 13 and 14 bent inwardly. This inward bending of the edges extends along approximately the entire length of the strip or elastic so that the elastic will have substantially a concavo convex shape laterally throughout its length. The crescent-shaped covering also gives the strip or elastic 12 a concave face longitudinally. This is clearly 75 illustrated in Fig. 5 in order to prevent the edges 15, which have been trimmed off, from ravelling, the edges are bound by means of stitching 21. This stitching is similar to button-hole stitching and effectually prevents the ravelling. The edges 13 and 14, of course, have a selvage. By this construction 80 it will be noted that I have devised a hat size reducer which is comparatively cheap to make, light in weight, and is ventilated to a certain extent since air can readily pass 95 through the fabric casing or covering 17.

It will also be noted that I have constructed a hat size reducer in which the face that contacts with the head is rounded laterally and is of considerable width so that 100 there will be no uncomfortable feeling on the head when the device is in use. This was one serious objection to hat size reducers which used a narrow elastic because the elastic would have a tendency to cut into the head of a wearer. My device also has the advantage of being cooler than a hat size reducer in which padding is used because this padding tends to heat up the head and 105 soaks up perspiration and, therefore, there is 110

always a great possibility of a hat size reducer, which is padded, of, in time, acquiring a disagreeable odor.

It will also be noted from Fig. 5 that the 5 prongs 11 not only project through the flexible member 8 but also through the casing or covering 17 and project rearwardly from the convex face of the pad.

It will be further noted from Fig. 6 that 10 the flexible strip 8 is on the outside of the metallic strip 9 so that when the prongs are pushed into the hat crown for attaching the reducer to a hat, a relatively wide surface will bear against the inside of the hat crown 15 so that any tilting tendency of the reducer when placing the hat on the head is eliminated.

It will also be noted that the prongs 11 are located substantially midway the longitudinal edges of the strip 8. This also has the advantage of preventing any tipping tendency of the reducer when removing the hat and by placing this strip 9 on the inner face of the strip 8, no metal is exposed except the prongs 4, which project from the casing, and by having the prongs passing through the strip 8, separate fastening devices for securing the strips 8 and 9 together are unnecessary.

While my device has all the advantages of having a relatively wide flexible strip to contact with the hat crown, the cost of manufacture is materially reduced by having a narrow metallic strip, since not alone is the cost of material saved in the strip itself, but the sleeves 10, which have the prongs 11, can also be made much smaller and consequently their cost is reduced. Then again by having the sleeves and strips 35 9 narrow, not alone is cost of material saved, but considerable weight is also eliminated and the outwardly bowed strip or compound member is rendered much more flexible than if a wide metal strip were used.

Having fully described my invention, 40 what I claim is:—

1. A hat size reducer comprising an arcuate flexible flat strip, a metallic strip located on the inside of said flat strip, fasten-

ing prongs projecting from the convex face 50 of said metallic strip and through said flexible strip, an elastic of less length and of greater width than said flexible strip having its ends secured to said flexible strip whereby said strips are bowed outwardly, 55 and a fabric covering for said strips and said elastic for drawing in said elastic so as to concave the same and place it under tension, said covering also adapted to bend the longitudinal edges of the elastic strip toward the flexible strip whereby a laterally convex face is formed along the elastic strip throughout the major portion of its length.

2. A hat size reducer comprising a crescent-shaped fabric casing, an arcuate rectangular flexible strip located within said casing along the convex edge thereof, a flexible metallic strip located along the concave face of said flexible strip, prongs projecting from the convex face of the metallic 70 strip through said flexible strip and through the convex face of said casing, an elastic strip of greater width than the flexible strip and having reduced ends secured at its ends to certain of said prongs whereby said flexible strip and metallic strip are bowed outwardly from said elastic, the crescent-shaped casing adapted to concave the elastic strip longitudinally and also to bend its longitudinal edges backward whereby the major 80 portion of the concave edge will be convexed laterally and a hollow pocket formed within the casing.

3. In a hat size reducer a crescent-shaped casing having a laterally concavo convex and longitudinally concave elastic in one edge, a rectangular flexible fiber board strip located along the convex edge of said casing, a flexible metal strip of less width than said fiber strip located intermediate the longitudinal 90 edges of said fiber strip, and a plurality of prongs carried by said flexible metal strip, said prongs extending through the fiber strip and through the casing whereby said reducer can be attached to a hat.

In testimony whereof I have affixed my signature.

LEON COHEN.
